(57) **CLAIM**

The ornamental design for a transparent case for a media cassette or video game cartridge as shown and described.

DESCRIPTION

FIG. 1 is a back perspective view of a transparent case for a media cassette or video game cartridge showing the new design according to a first embodiment.

FIG. 2 is an elevation view of the front thereof.

FIG. 3 is an elevation view of the back thereof.

FIG. 4 is an elevation view of the left side thereof.

FIG. 5 is an elevation view of the right side thereof.

FIG. 6 is an elevation view of the top thereof.

FIG. 7 is an elevation view of the bottom thereof.

FIG. 8 is a front perspective view thereof.

FIG. 9 is a back perspective view of the transparent case for a media cassette or video game cartridge according to a second embodiment.

FIG. 10 is an elevation view of the front thereof.

FIG. 11 is an elevation view of the back thereof.

FIG. 12 is an elevation view of the left side thereof.

FIG. 13 is an elevation view of the right side thereof.

FIG. 14 is an elevation view of the top thereof.

FIG. 15 is an elevation view of the bottom thereof.

FIG. 16 is a front perspective view thereof.

FIG. 17 is a back perspective view of the transparent case for a media cassette or video game cartridge according to a third embodiment.

FIG. 18 is an elevation view of the front thereof.

FIG. 19 is an elevation view of the back thereof.

FIG. 20 is an elevation view of the left side thereof.

FIG. 21 is an elevation view of the right side thereof.

FIG. 22 is an elevation view of the top thereof.

FIG. 23 is an elevation view of the bottom thereof.

FIG. 24 is a front perspective view thereof.

FIG. 25 is a back perspective view of the transparent case for a media cassette or video game cartridge according to a fourth embodiment.

(Continued)

FIG. 26 is an elevation view of the front thereof.
 FIG. 27 is an elevation view of the back thereof.
 FIG. 28 is an elevation view of the left side thereof.
 FIG. 29 is an elevation view of the right side thereof.
 FIG. 30 is an elevation view of the top thereof.
 FIG. 31 is an elevation view of the bottom thereof.
 FIG. 32 is a front perspective view thereof.
 FIG. 33 is a back perspective view of the transparent case for a media cassette or video game cartridge according to a fifth embodiment.
 FIG. 34 is an elevation view of the front thereof.
 FIG. 35 is an elevation view of the back thereof.
 FIG. 36 is an elevation view of the left side thereof.
 FIG. 37 is an elevation view of the right side thereof.
 FIG. 38 is an elevation view of the top thereof.
 FIG. 39 is an elevation view of the bottom thereof; and, FIG. 40 is a front perspective view thereof.
